JACK SEAL

Carl W. Roser, Newark, N. J., assignor to Western Electric Company, Incorporated, New York, N. Y., a corporation of New York

Application October 4, 1938, Serial No. 233,176

14 Claims. (Cl. 179—96)

This invention relates to jack seals, and more particularly to seals for telephone switchboard jacks.

5 In establishments, such as hotels, where it is desirable to temporarily retire certain telephone lines it has been found that this may be effectively accomplished by sealing the jacks of such lines against use.

An object of the invention is to provide a simple, efficient and practical seal for jacks.

With this and other objects in view, the invention comprises a hollow element slidably receivable in a jack sleeve and split so that it may be expanded by a conical member threaded into the element from the rear to lock the element within the jack sleeve, the front of the element being conditioned to receive a soft metal plug to close the element against access to the conical member.

Other objects and advantages will be apparent 20 from the following detailed description taken in conjunction with the accompanying drawing, wherein—

Fig. 1 is a side elevational view of one form of jack with the seal associated therewith;

25 Fig. 2 is an enlarged longitudinal sectional view taken along the line 2—2 of Fig. 1, and

Fig. 3 is an enlarged vertical sectional view taken along the line 3—3 of Fig. 1.

In the present embodiment of the invention 30 the seal is shown associated with one of several types of telephone jacks, indicated at 10 and having a sleeve 11 mounted in any suitable switchboard (not shown). The sleeves, such as sleeve 11, of jacks as a rule have standard inside dimensions for receiving a standard telephone plug. As shown in Figs. 1 and 2, the forward end of the sleeve is round at its aperture for readily receiving a switchboard plug.

The seal comprises a hollow or cylindrical element 14 substantially equal in diameter to the aperture of the sleeve, yet slidably receivable therein. The forward end of the sleeve is enlarged, as at 15, forming an abutting shoulder curving into the peripheral adjacent wall of the element to conform to the curvature of the sleeve aperture and to limit the inward movement of the element. At positions indicated at 16 and 17 the element is reduced in thickness throughout its circumference to add resiliency to gripping portions 18 formed by longitudinally extending slots 19. The reduced portions 16 and 17 further provide gripping edges which may intimately engage the inner wall of the sleeve 11 to prevent removal of the element when a conical member 20 is forced into locking position.

The conical member 20 is threaded for a portion of its length to interengage internal threads in the forward portion of the element. The rearward portion of the member, however, has a smooth surface substantially conical in shape and positioned to engage the inner walls 23 of the gripping portions 18. The inner walls 23 of the gripping portions are tapered slightly, as illustrated in Fig. 2, to reduce the force required for the member 20 to move them into locking relation with the sleeve. The forward portion of the conical member 20 may be conditioned to receive a tool to cause rotation of the member relative to the element in locking the element in a jack sleeve. In the present embodiment a screw driver slot 24 is illustrated for this purpose. The forward end of the element 14, which extends free of the sleeve 11 when the element is disposed therein, is tapered inwardly at an angle toward the center line of the element, as illustrated at 25, and terminates at a circular opening 26 for receiving a semi-spherical soft plug 27. The inner wall of the opening 26 is flared outwardly, as at 28, and terminates at its inner extremity adjacent a shoulder 29, which serves as a stop for the plug 27 when inserted in place. The plug 27, as illustrated in Fig. 2, is hollow and slightly smaller in diameter than the opening 26 so that it may be readily inserted therein. By applying sufficient pressure to the plug, after it has been disposed 30 in the opening the plug will tend to flatten, conforming to the tapered surface 28 of the opening and cause an interlocking relation of the plug and the element. A suitable tool (not shown) with a concaved plug engaging end, provided, 35 if desired, with projections to form configurations in the plug, may be used to force the plug in place.

Any desired jack may be rendered ineffective 40 for use by first placing the conical member with in the element and interconnecting the threads thereof, yet not to the extent to move the gripping portions outwardly. The seal thus assembled may be inserted into the sleeve 11 to the position shown in Figs. 1 and 2, and a tool such as a screw 45 driver may then be inserted in the element to cause rotation of the conical member therein until the gripping portions of the element are forced in engagement with the inner wall of the sleeve to prevent removal of the element. The plug 27 50 may then be inserted in place. The plug 27, being of soft metal, such as lead, will indicate any attempt to remove the seal from the jack. It is not intended that the jack be positively sealed against use, as the seal could be removed with- 55

out much effort but not without leaving evidence of the intention of removing the seal. The main purpose of the seal is to officially condition a desired number of jacks or telephone lines against 5 use temporarily and when thus sealed and allowed to remain sealed for the desired time there would be no charge for the service of such telephones. However, should the seal be broken, that is, should the plug 27 be removed or show indications of 10 being tampered with, the charge could be made for the service of the telephones connected to the jacks in which such tampered seals are located.

By using the jack seals to temporarily retire a selected number of telephone lines it is not necessary 15 to remove the telephones in said lines to condition the lines against service. The telephones may remain connected in the lines for future service and when such service is desired a properly authorized person may remove the 20 seals, again placing the telephones in service. The plugs 27 are sufficiently durable to keep the exposed end of the element closed and its semi-spherical contour renders it impossible to remove the plug without causing damage thereto to make 25 it impossible to again insert it in the element or leave some indication of having been tampered with. The plug 27, being hollow, will collapse when removed by a tool such as a pair of pliers.

The embodiment of the invention herein disclosed 30 is illustrative only and may be widely modified and departed from in many ways without departing from the spirit and scope of the invention as pointed out in and limited only by the appended claims.

35 What is claimed is:

1. A seal for a jack having a sleeve, the seal comprising a closure element receivable in a jack sleeve and having a resilient portion, and means to force the resilient portion into engagement with 40 the sleeve to rigidly secure the element therein.
2. A seal for a jack having a sleeve, the seal comprising a hollow element receivable in a jack sleeve, and means disposed in the inner end of the element to secure the element in the sleeve.
- 45 3. A seal for a jack having a sleeve, the seal comprising a hollow element receivable in a jack sleeve, and means disposed in the inner end of the element and accessible from the outer end of the element to secure the element in the sleeve.
- 50 4. A seal for a jack having a sleeve, the seal comprising a hollow element receivable in a jack sleeve, means disposed in the inner end of the element and accessible from the outer end of the element to secure the element in the sleeve, and 55 means to close the outer end of the element against access to the securing means.
5. A seal for a jack having a sleeve, the seal comprising a hollow element receivable in a jack sleeve and having a movable portion, and means 60 receivable in the element to move the said portion into intimate engagement with the sleeve to secure the element against displacement relative to the sleeve.

6. A seal for a jack having a sleeve, the seal comprising a hollow element receivable in a jack sleeve and having a movable portion, means receivable in the element to move the said portion into intimate engagement with the sleeve to secure the element against displacement relative to the sleeve, and means to close the hollow element. 5

7. A seal for a jack having a sleeve, the seal comprising a hollow element receivable in a jack sleeve and a member threadedly disposed in the inner end of the element and accessible through the outer end thereof to cause the element to be secured in the sleeve. 10

8. A seal for a jack having a sleeve, the seal comprising a hollow element receivable in a jack sleeve and a member threadedly disposed in the inner end of the element and accessible through the outer end thereof to cause the element to be secured in the sleeve, and means to close the outer end of the element against access to the member. 15 20

9. A seal for a jack having a sleeve, the seal comprising a hollow element receivable in a jack sleeve, means disposed in the inner end of the element and accessible from the outer end of the element to secure the element in the sleeve, and a soft metal member to close the outer end of the element against access to the securing means. 25

10. A seal comprising a hollow element split at one end to form resilient portions, a member threadedly movable in the element to move the portions outwardly and accessible from the other end of the element, and means to close the element against access to the member. 30

11. A seal comprising a hollow element split at one end to form resilient portions, a member threadedly movable in the element to move the portions outwardly and accessible from the other end of the element, and a soft metal cap to close the element against access to the member. 35

12. A seal comprising a hollow element split at one end to form resilient portions, a member threadedly movable in the element to move the portions outwardly and accessible from the other end of the element, and a hollow soft metal cap to close the element against access to the member. 40 45

13. A seal comprising a hollow element split at one end to form resilient portions, a member threadedly engaging the element having a tapered head to move the portions outwardly and accessible from the other end of the element, and means to close the element against access to the member. 50

14. A seal for a jack having a sleeve, the seal comprising a hollow element receivable in a jack sleeve split at its inner end to form resilient portions and grooved at its outer end, a member threadedly movable in the element to move the portions outwardly and accessible from the outer end of the element, and a soft metal cap disposed in the grooved outer end of the element to close the element against access to the member. 55 60

CARL W. ROSER.
